US00D954008S

(12) **United States Design Patent** (10) Patent No.: **US D954,008 S**
(45) Date of Patent: ** Jun. 7, 2022

(54) **VIDEOCONFERENCING UNIT**

(71) Applicant: **YEALINK (XIAMEN) NETWORK TECHNOLOGY CO., LTD.**, Fujian (CN)

(72) Inventor: **Jingfeng Su**, Fujian (CN)

(73) Assignee: **YEALINK (XIAMEN) NETWORK TECHNOLOGY CO., LTD.**, Xiamen (CN)

(**) Term: **15 Years**

(21) Appl. No.: **29/732,809**

(22) Filed: **Apr. 28, 2020**

(30) **Foreign Application Priority Data**

Mar. 27, 2020 (CN) 202030112473.7

(57) **CLAIM**

The ornamental design for a videoconferencing unit, as shown and described.

DESCRIPTION

FIG. 1 is a front elevational view of a videoconferencing unit showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and right side perspective view thereof; and,

FIG. 8 is a bottom, rear and left side perspective view thereof.

The broken lines in the drawings illustrate portions of the videoconferencing unit which form no part of the claimed design.

1 Claim, 4 Drawing Sheets
